UNITED STATES PATENT OFFICE.

ALLEN KINGHAN, OF HOQUIAM, WASHINGTON.

LETTER OR PACKAGE TYING DEVICE.

1,277,731.

Specification of Letters Patent. Patented Sept. 3, 1918.

Application filed January 10, 1918. Serial No. 211,193.

To all whom it may concern:

Be it known that I, ALLEN KINGHAN, a citizen of the United States, residing at Hoquiam, in the county of Grays Harbor, 5 State of Washington, have invented a new and useful Letter or Package Tying Device; and I do hereby declare the following to be a full, clear, and exact description of the invention, such as will enable others skilled 10 in the art to which it appertains to make and use the same.

This invention relates to an improved package or letter tying device, and an object of the invention is to provide an improved 15 fastener and a cord attached thereto, which is adapted to pass several times about the package as disclosed in the drawings, in combination with means on the fastener for detachably clamping the cord thereby holding 20 the package or bundle of letters securely tied.

In practical fields the details of construction may necessitate alterations falling within the scope of what is claimed.

25 The invention comprises further features and combination of parts as hereinafter set forth shown in the drawings and claimed.

In the drawings:—

Figure 1 is a plan view of a package 30 showing the improved tying device applied.

Fig. 2 is a perspective view of the fastener with which the cord coöperates for 35 tying the package.

Fig. 3 is a detail perspective view of a portion of the fastener, showing clamping 40 parts for clamping the cord.

Fig. 4 is a detail edge view of the fastener, showing deflected or bent parts of 45 the fastener for partly tilting the fastener from the face of the package, to allow a portion of the cord to pass under the fastener.

Referring more especially to the drawings 1 designates an improved fastener, 45 which is of a general substantially triangular shape, and consists of a skeleton frame. One corner of this frame is provided with a substantially circular ring 2, to be engaged by the thumb of the user or operator, to hold the fastener in position against 50 the package to be tied. Another corner of the frame of the fastener is deflected or bent outwardly from the face of the package 3, as shown at 4, and is provided with 55 an aperture or opening 5, in which one end portion of a cord 6 is attached by

forming a knot 7 in the extremity of the cord. Another corner portion of the frame of the fastener is constructed with a compound curved part 8. One loop 9 of this 60 part 8 is deflected or bent toward the face of the package to engage therewith, whereby the loop 10 may be held slightly spaced from the face of the package, whereby the cord 6 may pass under said loop 10. Rising 65 outwardly and curved from one side of the loop 10 is a tongue or projection 11, which comprises the enlargement 12 and the restricted neck portion 13, which is between 70 the enlargement and where the tongue integrally projects from the side of the loop 10. The enlargement 12, is nearly in parallelism with the face of the frame of the fastener, with exception of its extremity, which is slightly deflected outwardly, to 75 guide a portion of the cord into a looped engagement with the neck 13. In tying a package, the frame or the fastener is held by the thumb on one face of the package in the position as shown in Fig. 1, and the cord 80 6 passes about the package in the direction of the arrow *a*, under the package and over the same in the same direction as indicated by the arrow *b*. The portion 14 of the cord then passes under the loop 10 and engages 85 the crotch 15 of the loop 16 of the compound curved part of the frame 1. The cord after engaging the crotch 15 extends in the direction of the arrow *c* transversely over and under and a second time over the package 90 as indicated by the arrow *c*, whereby the portion 17 of the cord may engage the neck 13 of said tongue 11. The cord immediately at the point where it merges from engagement with the neck 13 engages and wedges or 95 binds against the cord, where it engages the crotch 15 of the loop 16 thereby securely holding the cord tight and tying the package. The cord in passing over the face of 100 the package which is engaged by the fastener passes over the frame of the fastener and assists in holding the fastener in place.

The invention having been set forth what is claimed as new and useful is:—

1. In a package tie, a skeleton fastener 105 frame having one corner provided with an aperture in which one end of a cord is adapted to be attached, another corner of said frame having a crotch with which a tying cord is adapted to engage after passing 110 about the package, said last named corner having a curved tongue, said curved tongue

being provided with a restricted neck to be engaged by the cord, which in turn binds against that portion of the cord engaging said crotch, said tongue having an enlargement at its extremity to hold the cord in engagement with said neck, and where the enlargement merged from the neck, means is provided, whereby the cord adjacent the neck binds against the cord engaging said 10 crotch, and means adjacent the crotch corner of the frame for holding the frame spaced from the package whereby said cord may pass under the frame.

2. In a package tie, a skeleton fastener 15 frame, to one corner of which one end of a cord is adapted to be connected, another corner of said frame having a crotch with which said cord is adapted to engage after passing about the package, a curved tongue rising 20 integrally and upwardly from the last

named corner and being provided with a restricted neck, said neck adapted to be engaged by the cord being so arranged relative to the crotch, whereby the cord engaging the neck will bind against the cord 25 which engages the crotch, said tongue having an enlargement at its extremity to retain the cord in engagement with the neck, said frame adjacent the crotch being bent to form a protrusion to engage the package, 30 whereby the frame is held spaced from the package to permit the cord to pass under the frame.

In testimony whereof I have signed my name to this specification in the presence of 35 two subscribing witnesses.

ALLEN KINGHAN.
